(57) **CLAIM**

The ornamental design for an ultrasonic cleaner, as shown and described.

DESCRIPTION

FIG. 1 is a front, bottom perspective view of an ultrasonic cleaner, showing my new design;

FIG. 2 is a rear, top perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of detail 9 in FIG. 7.

The dashed broken lines in the figures are for the purposes of illustrating portions of the ultrasonic cleaner that form no part of the claimed design.

The short-short-long dashed broken lines immediately adjacent to the claim area in the FIG. 2, FIG. 7 and FIG. 9 are for the purposes of illustrating the boundaries of the ultrasonic cleaner, and form no part of the claimed design.

The dash-dot-dash broken lines are for notating enlarged views and form no part of the claimed design.
